UNITED STATES PATENT OFFICE

DON HEYER, OF LOS ANGELES, CALIFORNIA

DESIGN FOR A MASSAGING OSCILLATOR

Application filed May 13, 1930. Serial No. 35,624. Term of patent 3½ years.

To all whom it may concern:

Be it known that I, DON HEYER, a citizen of the United States, residing at Los Angeles, in the county of Los Angeles and State of California, have invented a new, original, and ornamental Design for Massaging Oscillator, of which the following is a specification, reference being had to the accompanying drawing, forming part thereof.

Figure 1 is a front perspective view of a massaging oscillator, showing my new design; and

Figure 2 is a plan view of the same.

The ornamentation is not continued throughout the front of the article, but is to cover that portion of the front illustrated in the drawing.

I claim:

The ornamental design for a massaging oscillator, as shown and described.

DON HEYER.
